CLAIM

The ornamental designs for lighting fixtures, as shown and described.

DESCRIPTION

FIG. 1 is a bottom perspective view of a first embodiment of a lighting fixture downrod depicting our new design.

FIG. 2 is a top perspective view thereof;

FIG. 3 is a front elevational view thereof;

FIG. 4 is a back elevational view thereof;

FIG. 5 is a right elevational view thereof;

FIG. 6 is a left elevational view thereof;

FIG. 7 is a top plan view thereof; and,

FIG. 8 is a bottom plan view thereof;

FIG. 9 is a bottom perspective view of a second embodiment of a lighting fixture downrod depicting our new design.

FIG. 10 is a top perspective view thereof;

FIG. 11 is a front elevational view thereof;

FIG. 12 is a back elevational view thereof;

FIG. 13 is a right elevational view thereof;

FIG. 14 is a left elevational view thereof;

FIG. 15 is a top plan view thereof; and,

FIG. 16 is a bottom plan view thereof.

The break lines in FIGS. 9-14 indicate that the appearance of any portion of the lighting fixture downrod between the break lines forms no part of the claimed design. The broken lines depicted in the view represent environment which forms no part of the claimed design.

1 Claim, 14 Drawing Sheets
